DESIGN FOR A WHIRLING TOY

Richard F. Summers, New York, N. Y.

Application April 10, 1946, Serial No. 128,455

Term of patent 3½ years

(Cl. D34—15)

To all whom it may concern:

Be it known that I, Richard F. Summers, a citizen of the United States, residing at the Borough of Manhattan, in the county of New York, city and State of New York, have invented a new, original, and ornamental Design for a Whirling Toy, of which the following is a specification, reference being had to the accompanying drawing, forming part thereof.

Fig. 1 is a front elevational view of a whirling toy showing my new design.

Fig. 2 is a fragmentary side elevational view thereof.

Fig. 3 is a horizontal sectional view thereof taken on the line 3—3 of Fig. 1.

I claim:

The ornamental design for a whirling toy, substantially as shown.

RICHARD F. SUMMERS.
